UNITED STATES PATENT OFFICE.

MICHAEL CLINTON, OF PHILADELPHIA, PENNSYLVANIA, ASSIGNOR OF ONE-FOURTH TO PENN PRINTING HOUSE, ONE-FOURTH TO HARRY MILLER, OF DELAWARE COUNTY, AND ONE-FOURTH TO WILLIAM E. CUNNINGHAM, OF PHILADELPHIA, PENNSYLVANIA.

PAPER-HEATER FOR PRINTING-PRESSES.

1,131,642.

Specification of Letters Patent.

Patented Mar. 9, 1915.

Application filed April 23, 1914. Serial No. 834,016.

To all whom it may concern:

Be it known that I, MICHAEL CLINTON, a citizen of the United States, residing at Philadelphia, in the county of Philadelphia and State of Pennsylvania, have invented 5 certain new and useful Improvements in Paper-Heaters for Printing-Presses, of which the following is a specification.

By heating the paper and the cylinder 10 packing of the cylinder of printing presses, a number of useful purposes are attained; the charge of static electricity formed upon the sheet of paper is so lessened that the paper is easily handled; the ink is more 15 quickly dried; the quality of the printing is improved, and various other advantages that will appear from the specification are secured.

Figure 1 is a front view of a portion of a 20 press showing my invented device and the parts most nearly connected with it. Fig. 2 is a side elevation of the parts shown in Fig. 1. Fig. 3 is a section on line $x-x$ of Fig. 1. Fig. 4 is a section, on the line $x-x$ 25 of Fig. 2, of a slightly modified form of the heated cylinder. Figs. 5 and 6 are top and bottom views of the bridge cam. Fig. 7 is a side elevation of the revoluble steam coupling; Fig. 8 is a front elevation of a 30 heating cylinder and cylinder of the press; Fig. 9 is a side elevation of the parts shown in Fig. 8. Fig. 10 is a view of the stop used in the devices for giving a yielding motion toward the cylinder; Fig. 11 is a detail showing 35 the roller bearing mounting of the paper heating tube; Fig. 12 a detail of the mounting of the tube from the frame of the press, and Fig. 13 a detail showing the mounting of the guide wheels.

40 In the portion of the press shown 5 is the cylinder, 27, the cam box; 30 the paper finger shaft, 31, the arm connecting it to the cam box, 33 the side frame of the press, 25 an arm connecting with the cam box; and 45 67 the cylinder shaft.

The heating cylinder 3 of my invented device is parallel to the cylinder 5, and is freely rotatable. It incloses steam pipe 9 that runs longitudinally through it. This 50 steam pipe is connected to a source of steam supply (not shown) which can be either exhaust or live steam. The cylinder 3 is mounted upon the pipe 9 by roller bearings held in case 1, which are placed at the ends

of the cylinder 3 (see Fig. 11) and enable 55 the cylinder to revolve very freely so that slight frictional contact between it and the surface of the cylinder or the paper, will revolve it. The even heating of cylinder 3 throughout its length is promoted by keeping 60 the space between the interior of its walls and the steam heated metal small. This can be done by placing an extra tubing 4 over the pipe 9, (see Fig. 3) or by connecting the pipe 9 to a larger pipe 2, which 65 nearly fills the cylinder 3. (See Fig. 4.)

The cylinder 3 is held, during a part or the whole of the cylinder 3 revolution in yielding contact with it. Cases arise, however, when it is desired to give the cylinder 70 3 a fixed position, and cases when it is desirable to limit its motion toward the cylinder 5. The pipe 9 is mounted on standards 8 from a shaft 14 of the press. Each 75 of these standards is provided with set screws 7, 7. The springs 13, 13 hold the cylinder 3 yieldingly against the cylinder 5. These springs 13, 13, are attached to the ears 16, 16, on the frame 33 and to the pipes 11. The elbows 10, 10 connect the pipes 9, 9, 80 to the pipes 11, 11. If the give of the pipes is not sufficient to allow cylinder 3 to be brought into contact with the cylinder 5 by the springs 13, 13, I use a revolving coupling (see Fig. 7) in which the coupling 15 85 is rigidly connected to the pipe 11, while the pipe 17 is rotatably connected and is supported by the standard 18.

In cylinder presses there is usually a space where the surface of the cylinder is 90 open, or where there is something on the surface of the press cylinder which the cylinder 3 must be pushed back to allow to pass. A cam, 50, 50, bridges the open space in the cylinder 5 and carries the cylinder 3 over 95 the open space. The cams, 50, 50, can be raised sufficiently to push back the cylinder 3 so that it will clear the fingers 53. A convenient form of this cam construction is shown in Figs. 4, 5 and 6, where the cam is 100 provided with rider 56, having sloping ends 57, 57. The lugs 51 and 54 fit back of the walls of the cylinder 5, and are provided with the set screws, 53 and 58. Screw 53 passes through the rider 56, and the wall of 105 cylinder 5, and screw 58 passes through lug 54 and clamps against the interior of wall of cylinder 5. The Figs. 8 and 13 serve to

illustrate a form where the flanged wheels 64, 64 are mounted on the pipe 9 and running on the end hoops 71, 71, of the cylinder 5, are used to preserve the distance between 5 cylinders 3 and 5. 69 is a ball bearing placed between pipe 9 and wheel 64. Where a lift is to be given, to cylinder 3, for instance, to pass over the fingers 30 or the sockets 65 and 66, a rider cam 68 is placed 10 on the cylinder end hoop 71 where this push is desired to be given.

Where it is desired that the movement of the cylinder 3 toward the cylinder 5 be limited, a slot is cut extending part way around 15 the shaft 14, so that by projecting set screw 7 into it the revolution of link 8 upon it is limited. This slot can have two steps 61, 62, so that by projecting the screw 7 to varying depths in the socket 63, the amount of the 20 rotation permitted to link 8 can be varied. The set screws 7 may also be set tight and the link 8 held in rigid position.

I claim:

1. The combination with the cylinder of a 25 printing press of a revolving heated cylinder yieldingly impelled toward the cylinder of the press.

2. The combination with the cylinder of a printing press, of a heated cylinder, yieldingly impelled toward the cylinder of the 30 press, and stops limiting the movement of the heated cylinder toward the cylinder of the press.

3. The combination in a paper heater for 35 printing presses, of a heating pipe, and a freely revoluble cylinder surrounding the heater pipe and turning on roller bearings thereon, the exterior walls of the heating pipe between these bearings lying close to 40 but not touching the interior of the cylinder,

and being of substantially larger size than the portions of the heater pipe carrying the bearings.

4. The combination, in a paper heater for 45 printing presses, with the cylinder of a printing press of a heating cylinder yieldingly impelled toward the cylinder of the printing press and a distance maintainer, operatively connected between the heated cylinder and the cylinder of the press.

5. The combination, in a paper heater for 50 printing presses, with the cylinder of a printing press, of a heated, freely revoluble cylinder, yieldingly impelled toward the cylinder of the printing press, of wheels moving toward and from the press cylinder with the heated cylinder but revoluble independently of the latter, and running upon the press cylinder.

6. The combination, in a paper heater for 55 printing presses of a freely revoluble heated cylinder, with the press cylinder, a space maintainer operatively connected between the press cylinder and the heated cylinder and a spacing cam upon the press cylinder. 65

7. In a paper heater for printing presses, the combination with the cylinder of a printing press, of a shaft having a slot therein extending part way around the shaft, a link revoluble about this shaft, a set screw set in 70 said link and projecting into the slot in this shaft, a heating pipe and a revoluble heated cylinder carried by the heating pipe.

In testimony whereof I affix my signature in presence of two witnesses.

MICHAEL CLINTON.
